UNITED STATES PATENT OFFICE.

SIDNEY LOVELL, OF CHICAGO, ILLINOIS.

MAUSOLEUM CONSTRUCTION.

1,244,109.

Specification of Letters Patent. Patented Oct. 23, 1917.

Application filed May 16, 1917. Serial No. 168,941.

To all whom it may concern:

Be it known that I, SIDNEY LOVELL, a citizen of the United States, residing at Chicago, in the county of Cook and State of Illinois, have invented a certain new and useful Improvement in Mausoleum Constructions, of which the following is a full, clear, concise, and exact description, reference being had to the accompanying drawings, forming a part of this specification.

My invention relates to mausoleum constructions, and especially to a system for ventilating the individual crypts or vaults thereof.

Prominent objects of the invention are to provide a simple, practical and effective construction of mausoleum and ventilating system therefor; to permit the same to be economically constructed and quickly and inexpensively installed; and to secure the foregoing and other desirable results in a simple and expeditious manner.

In the accompanying drawings Figure 1 is a vertical section of a mausoleum construction and ventilating system therefor embodying my present invention;

Fig. 2 is a vertical section of a portion of the same;

Fig. 3 is a cross section taken on line 3-3 in Fig. 2; and

Fig. 4 is a perspective view of a detail of construction.

In the arrangement shown for carrying out the invention a mausoleum structure 1 is shown, the same having a floor 2 and an entry door 3. A series of vaults or crypts 4 are shown arranged one above the other, although of course the same may be arranged in various ways. In the uppermost vault 4 is shown a coffin 5.

The invention relates more especially to the arrangement by which these vaults or crypts can be ventilated, preferably by a continuous current of air circulating through the same. To such end I show the rear ends of the vaults provided with apertures in which are placed or fitted tubular members 6 and 7. These members 6 and 7 are substantially alike except that they are in up-side-down or reversed positions with reference to one another. Each member as best shown in Fig. 4, comprises a tubular or box-like structure or casing conveniently of rectangular cross section, although of course this may be varied. In the member 7 shown in Fig. 4 the top 7a is provided with a re-

cess or cutaway portion 8 and the bottom 7b with a projecting member or tongue 9. In the case of the member 6 the reverse is true, the top being provided with the tongue 9 and the bottom with the recess 8. These members 6 and 7 are used in connection with and are fitted to a pipe 10 which is extended vertically in the rear wall of the mausoleum in the rear of the vaults 4. A member 6 is preferably used at the bottom of each vault in which case the tongue 9 projects into the pipe 10 and contacts with the rear wall of the same, thereby closing said pipe against upward movement or circulation of air therein, and consequently deflecting air in said pipe laterally and into and through the member 6 into the interior of the vault 4. Similarly a member 7 is fitted in position so that its tongue 9 also closes the pipe 10 against movement or circulation of air or the like, except in an upward direction, in each case the recessed portion 8 fitting snugly to the pipe 10 and making an air tight joint therewith. To accommodate the members 6 and 7 the pipe 10 is preferably provided with laterally extending ears 11 which fit closely against the outer vertical side walls of said members 6 and 7, as best shown in Figs. 2 and 3. Bolts 12 may be extended through the side members 11 and also through the ends of the members 6 and 7 between the same, so as to form a tight and firm connection between the members 6 and 7 and the pipe 10. Thus it will be seen that air or other fluid passing into one end of the pipe 10 will be circulated through the vaults 4 into and out of one vault, and thence into and through the pipe 10 to the next vault, and into and out of that, and so on through the series. A coöperating pipe 14 is provided, preferably in the rear of the pipe 10, and these two pipes 10 and 14 are conveniently led to the basement 15 or other convenient place, where suitable apparatus is provided for inducing a circulation through the series of vaults. As a convenient arrangement I show an electric motor 16 driving a fan or blower 17 which latter is connected with the pipe 14 by means of an inlet pipe 18, the blower 17 being preferably such as to force air through the pipe 18 and into the pipe 14 and from the latter downwardly through the vaults 4 in a downward direction, entering each vault at the top and circulating through the same and leaving it at

the bottom. An antiseptic tank 20 is also shown connected with the pipe 10 by a connecting pipe 21 having a valve 22. In this way the air coming from the vaults 5 passes through the antiseptic tank and is purified before being delivered into the outer air or back again into the blower 17, as the case may be.

It will be understood that changes and 10 modifications may be made without departing from the spirit of the invention.

What I claim is:

1. The combination with the vaults or 15 crypts of a mausoleum, of a circulation pipe and tubular members extending between said circulation pipe and the interior of said vaults or crypts, said tubular members being provided with means for stopping the circulation of air in said pipe and 20 directing it into and out of said vaults or crypts.

2. The combination with the vaults or 25 crypts of a mausoleum, of a circulation pipe and tubular members extending between said circulation pipe and said vaults or crypts, said tubular members being provided with 30 projections extending crosswise of said circulation pipe to stop the current of air therein and deflect the same into the vaults or crypts.

3. The combination with the circulation pipe of tubular members associated therewith, said tubular members being provided with projections extending crosswise of the circulation pipe and also with recessed portions to fit the shape of said pipe, the projections and recessed portions being arranged alternately in the successive members. 35

4. The combination with a circulation 40 pipe provided with side apertures and laterally extending lugs or projections at the edges of said apertures, of tubular members fitted to said circulation pipe at said apertures, said tubular members having projections extending into and across said circulation pipe and fitting the interior wall of the same, said members also having cut-away portions adapted to fit the shape of 45 said pipe, said tubular members fitting and being secured between the side lugs on said pipe, whereby circulation in said pipe is stopped and deflected outwardly through 50 said tubular members.

In witness whereof, I hereunto subscribe 55 my name this 26th day of May A. D., 1916.

SIDNEY LOVELL.
